UNITED STATES PATENT OFFICE.

RUDOLPH WEHR, OF NEW YORK, N. Y.

INTERNAL-COMBUSTION ENGINE.

1,273,433.

Specification of Letters Patent. Patented July 23, 1918.

Application filed June 20, 1917. Serial No. 175,847.

To all whom it may concern:

Be it known that I, RUDOLPH WEHR, a subject of the King of Hungary, and a resident of the city of New York, in the county 5 of New York and State of New York, have invented certain new and useful Improvements in Internal-Combustion Engines, of which the following is a specification.

The present invention relates to internal 10 combustion engines, and more particularly to the type which is provided with rotary valves.

The main object of the invention is to provide a packing or lining for the valve 15 chambers of the engine, which automatically adjusts itself to compensate for the wear thereof.

Another object of the invention is to provide a lubricating system for the valve seats 20 of the engine, which is simple in construction, efficient in operation, and prevents the gases, fuel and the exhaust gases, respectively, from passing from any one of the cylinders of the engine to the adjoining 25 ones.

With these and other objects in view, which will more fully appear as the nature 30 of the invention is better understood, the same consists in the combination, arrangement and construction of parts hereinafter described, pointed out in the appended claims and illustrated in the accompanying drawings, it being understood that many changes may be made in the size and proportion 35 of the several parts and details of construction within the scope of the appended claims without departing from the spirit or sacrificing any of the advantages of the invention.

One of the many possible embodiments of 40 the invention is illustrated in the accompanying drawings, in which:

Figure 1 is a top plan view of a portion of an internal combustion engine having the improvement mounted thereon; Fig. 2 is a section taken on line 2—2 of Fig. 1; Fig. 3 is a portion of a section taken on line 3—3 of Fig. 1; Fig. 4 is a perspective view, partly in section, of the rotary valve of the 50 engine; Fig. 5 is a perspective view of a section of the packing; Fig. 6 is a perspective view of a section of the packing, cooperating with the one shown in Fig. 5; and Fig. 7 is a plan view of the development 55 of the valve casing, showing the relation of the several ports therein.

Referring now to the drawings, the nu-

meral 10 indicates one of the working cylinders of the engine, provided for the well-known purpose, with a water jacket 11. In 60 this cylinder reciprocates a piston 12 of any suitable construction. For igniting the successive combustible charges supplied to the cylinder, a sparking device 13 of any suitable type is provided. On the top of the 65 engine, which is of the multi-cylinder type, are formed two valve casings 14, one on each side of the engine, and both running parallel to the crank shaft thereof (said crank shaft being not shown). The purpose of 70 providing two valve chambers is to enable the inlet and exhaust ports to be made of smaller sizes, inasmuch as two rotary valves are thus being made use of, instead of the usual single valve. The valve chambers and 75 so also the rotary valves are alike in construction, so that herein the description of only one chamber and one valve becomes necessary.

Each valve chamber communicates with 80 the cylinders of the engine through ports 15, and each chamber has inlet ports 16 and outlet ports 17, the number of the inlet ports in each chamber being equal to the number of outlet ports therein, and corresponds to that of the number of cylinders. The inlet ports 16 communicate with a fuel supply pipe 18, and the outlet ports 17 with an exhaust pipe 19.

Within each valve chamber is disposed a 90 rotary valve 20. These valves are actuated from the crank shaft of the engine by any suitable gearing (not shown). The valves rotate at a speed half of that of the crank shaft, or in other words, while the crank 95 shaft makes two revolutions each valve completes one turn, as usual in four cycle internal combustion engines. Each valve is provided with peripheral notches 21, corresponding to the number of ports 15 leading 100 to the respective valve chamber. These notches are in each valve staggered in the same manner as the several cranks of the crank shaft are set in relation to one another.

In order to prevent gases from flowing from one cylinder to another one, there are provided in the valve casing suitable packings between each two adjoining notches 21 in the valve therein. For this purpose there 110 are provided in each valve chamber, between the ports 15, packing housings 22, closed by covers 23, which are held on the housings by any suitable means, for instance screw-bolts 24.

In each housing is disposed a packing block 25, the underface 26 of which is concave, its curvature conforming to that of the valve, so as to snugly fit the same. The sides 27 of the blocks are flat, to fit those of the packing housings, whereby the blocks are guided in their movements toward the valve. The upper face of 28 of each block is slanting, and upon the same rests a wedge 29, provided 10 with a spindle 30, which extends through one of the sides of the packing housing and also through an extension 31 upon the respective cover 23. This extension is cylindrical and provided with exterior screw- 15 threads 32, meshing with those of a cap 33, within which is disposed a spring 34, that has a tendency to shift the wedge 29 inwardly.

With each valve chamber are associated 20 two channels, denoted by the numerals 35 and 36. Into these channels is forced, by any suitable feeding means, lubricating material, the channel 35 serving to supply lubricating material to those portions of the 25 valve seats which are disposed between the ports 15 and 17, and the channel 36 to those portions of the valve seat which are located between the ports 15 and 16. Between each port 15 and 17 extends throughout the 30 lengths thereof a longitudinal groove 37, and between each port 15 and 16 a longitudinal groove 38. Adjacent to each groove 37 leads from the surface of the valve seat a bore 39 to the channel 35, and adjacent to each 35 groove 38 a bore 40 to the channel 36. In the valves are formed, in alignment with each set of bores 39 and 40, peripheral grooves 41, into which is forced, through the said bores, a supply of lubricating material, and from which it is conducted into the 40 grooves 37 and 38, to be distributed, in turn, from the latter over the valve seats.

The packing blocks 25 are, preferably, made of gray iron, which is somewhat softer 45 than the material of which the valves are formed.

The operation of this device is as follows: Let us suppose that the packing blocks are in the positions shown in Fig. 3 of the drawings. The springs 34 force the wedges 29 inward, thereby causing the said blocks to contact throughout the entire areas of their concave under surfaces 26 with the valves, thereby forming an air-tight closure, so as to prevent the pressure in the working chambers of the cylinders from being lowered by leakage and also to prevent gases from flowing from one cylinder to another one. As, in use, the packing blocks wear off, the 50 springs 34 cause the said blocks by the intermediary of the wedges 29 to be lowered and to make continuously an air tight clo-

sure. The tension of the springs 34 may be varied by turning the caps 33 in one or the other direction, as desired.

65

What I claim is:

1. In a multi-cylinder internal combustion engine, the combination with a cylinder of the engine having a port, of a valve casing thereon provided with a corresponding inlet and an outlet, a rotary valve arranged in said casing having means for periodically opening and closing communications between said port and said inlet and outlet, a packing housing disposed at the side of said port, a packing block shiftably disposed in said housing having a concaved face abutting against said valve and a slanting face opposite to said concaved face, a spring-pressed wedge shiftably disposed in said housing bearing against the slanting face of said block, and means disposed outside of said housing for adjusting the pressure exerted by said wedge upon said block.

70

2. In a multi-cylinder internal combustion engine, the combination with a cylinder of the engine having a port, of a valve casing thereon provided with a corresponding inlet and an outlet, a rotary valve arranged in said casing having means for periodically opening and closing communications between said port and said inlet and outlet, a packing housing disposed at the side of said port, a packing block shiftably disposed in said housing having a concaved face abutting against said valve and a slanting face opposite to said concaved face, a wedge shiftably disposed in said housing bearing against the slanting face of said block, means for causing said wedge to continuously force 90 said block against said valve, and means disposed outside of said housing for adjusting the pressure exerted by said wedge upon said block.

85

3. In an internal combustion engine, the combination with the cylinder of an engine, of a valve casing thereon, a rotary valve arranged in said casing, and a divided valve seat within said casing, the working face of each section of said valve seat being provided with a longitudinal groove, with each section of said valve seat being associated a channel containing a supply of lubricating material communicating through a bore with the working face of the respective section of the valve seat, said valve being provided with a peripheral groove periodically communicating with the supply of lubricating material in said channels and with the longitudinal grooves in said valve seat sections.

105

Signed at New York, in the county of New York, and State of New York, this 22nd day of May, A. D. 1917.

RUDOLPH WEHR.
